UNITED STATES PATENT OFFICE.

ARTHUR E. READ, OF NEW YORK, N. Y.

ELECTRIC SWITCH.

1,279,437.

Specification of Letters Patent. Patented Sept. 17, 1918.

Application filed September 12, 1917. Serial No. 199,921.

To all whom it may concern:

Be it known that I, ARTHUR E. READ, a citizen of the United States, and a resident of the borough of Manhattan, city, county, and State of New York, have invented certain new and useful Improvements in Electric Switches, of which the following is a specification.

My improvements relate to the type of one-push-button electrical switch set forth particularly in my concurrent application No. 181,955, filed July 21, 1917, in which electrical contact is made and broken instantaneously with a snap which eliminates 10 sparking and injury to the terminals, the burning out of which is thus obviated as therein set forth. The main object of my present invention is to visualize the position of the switch,—i. e., to indicate externally 15 whether the electric circuit is open or closed; and the invention includes certain incidental features in the construction and arrangement of parts hereinafter described and claimed specifically,—a distinctive feature being the provision of shoulders on the rotatable blade or circuit closer which are engageable alternately with a shoulder on the actuating pawl to hold the push button in depressed position when the circuit is 20 open, thereby indicating the fact by the color of the portion of the push button shank left visible, whereas when the circuit is closed the protrusion of the shank of the push button to the fullest extent reveals a 25 portion of said push button which is of a different color from the extreme outer portion thereof, so that a glance at said shank will indicate whether the circuit is open or closed. Thus in the case of a light circuit 30 where the lamps are invisible from the switch the manipulator thereof can readily ascertain whether the lights are on or off by merely observing the protuberant portion of the shank of the push button.

For convenience of illustration the accompanying drawings are drawn on a much larger scale than is necessary for commercial purposes,—the device itself occupying approximately only one fourth the space shown.

Figure 1, is a central vertical sectional elevation showing the switch installed upon a suitable fixed support;

Fig. 2, is a perspective view with the cas-

ing omitted, and part of the base core 55 broken away;

Fig. 3, is a section of the casing with the otherwise inclosed parts in elevation, and in the relative positions in which the circuit is closed;

Fig. 4, is a view like unto Fig. 3, showing the operative parts in open circuit position;

Fig. 5, is a transverse section taken upon plane of line 5—5, Fig. 1;

Fig. 6, is a perspective view of one of 65 the terminals;

Fig. 7, is a perspective view of the rotatable circuit closer;

Fig. 8, is an inner end view showing the 70 terminal connections;

Fig. 9, is a diagrammatic view illustrating the operation of the rotatable circuit closer;

Fig. 10, is a sectional detail showing the 75 engagement of the spring pawl with the circuit closure blade.

The base core B, is preferably cylindrical in general configuration, being formed with a central compartment b, in which the terminals C, C', and rotatable circuit closer D, are situated, and with an annular shoulder 80 b', against which the inner edge s, of the shell S, abuts. This shoulder b', is of the same width as the thickness of the shell S, so that the joint between the latter and the base core B, is flush externally. The base 85 core B, is made of any desired non-conductive material, and is of such simple form that it may be conveniently molded or cast in quantities at relatively small cost,—its configuration adapting it to be readily 90 drawn from the matrix, and calling for little or no "finishing."

To the floor of the compartment b, of the base core B, are secured the circuit terminals C, C', by means of screws c, c, which 95 pass through the base core as shown in Fig. 1, and engage with bridge nut plates c', c', with which the circuit wire binding screws c", c", are connected, as shown particularly in Figs. 1, and 8.

As will be seen by reference to Figs. 2, 3 and 4, the duplex circuit terminal C, is formed of a single piece of sheet metal bent over upon itself to constitute the medial base c", for the opposed twin-spring jaws 105 c', which are bent toward each other, the extremities being flared outward slightly to facilitate the intrusion between them of the

circuit closer blade d , into the position shown in Figs. 1, 2 and 3.

The other or bifurcated circuit terminal C' , is also formed of a single strip of sheet metal bent up to constitute the base c' , and the spring jaws c'' , the latter formed by the creation of the slot c'' , between them for the accommodation of the circuit closer blade d , with which however they do not contact but merely straddle when said circuit closer blade d , is in the position shown in solid lines in Figs. 1, 2, 3 and 5.

The rotatable circuit closer D , consists of the bridge or contact blade d , and the ratchets d' , d'' , secured thereto, one on each side thereof. The ratchets d' , d'' , as well as the circuit closing blade d , are of metal, and each has four apices or teeth d^2 . The ratchets d' , d'' , constitute essentially the hub 20 of the rotatable circuit closer D , said hub being four-sided for engagement with the bifurcated spring terminal C' , which also performs the function of a detent to hold said rotatable circuit closer D , stationary 25 except when partially rotated by the depression of the spring pawl E . The pivot pin d^3 , on which the circuit closer rotates is supported in the side walls of the compartment b , of the base core B .

30 The push button P , comprises the body or flange-portion p , which is positioned within the cylindrical shell S , and the finger bearing or stem p' , which protrudes through the opening s' , in the escutcheon plate S' , which latter in the construction shown in the drawings closes the outer end of the shell or easing S . Interposed between the opposed end of the base core B , and the flanged portion p , of the push button P , is a helical spring 35 h , which tends constantly to press the push button outward. Rigidly secured to the inner side of the flanged portion p , of the push button P , is a guide plate Q , the parallel arms g , g , of which extend longitudinally 40 and into grooves b^2 , b^2 , formed for them in opposite sides of the base core B , (see Figs. 4 and 5) the side walls of said grooves b^2 , b^2 , acting as guide ways for said parallel arms g , g , which thus insure the proper alinement 45 of the parts and prevent the push button from turning on its axis. A stop b^3 , (Figs. 3 and 4) limits the inward thrust of the push button and connections.

One of the latter is the spring pawl E , which is rigidly attached to the inner side of the push button P , by the screw p^x , which also secures the guide plate Q , in position as shown in Fig. 1. The free end e , of said spring pawl E , is bifurcated to straddle the bridge blade d , and its prescribed thrust is just sufficient to carry the teeth d^2 , d^2 , of the ratchets d' , d'' , with which it is engaged only slightly beyond the axis d^2 , of the rotatable circuit closer D , or over the dead center, 60 when the spring terminal C' , completes the

one fourth rotation of the circuit closer, forcing it over until it contacts with the next succeeding flat sides of the ratchets d' , d'' . This action is exemplified diagrammatically in Fig. 9, in which the result of the thrust 70 of the spring pawl E , is illustrated in dotted lines, and the completion of the quarter turn of the circuit closer is shown in solid lines, this being the normal position of the spring terminal C' , as related to the ratchets d' , d'' . In other words, the spring pawl E , turns the circuit closer D , over, say 46° , and the spring terminal forces or "snaps" it over the other 44° , as indicated in said diagram Fig. 9. Thus a relatively short stroke of the 80 spring pawl E , is sufficient to insure a quick "make" or "break" of the electrical circuit by means of the rotatable contact blade d —the sudden (practically instantaneous) opening or closure of the circuit effected by 85 the spring terminal C' , effectually preventing "sparking" and consequent burning out of contacts.

Each extremity of the bridge blade d , is formed on one side with a concentric ridge 90 or shoulder d^4 , and one limb of the bifurcated free end e , of the spring pawl E , is formed with an inturned hook shoulder e' , which engages alternately with one or the other of said shoulders d^4 , on the bridge 95 blade d , when the latter is turned into open circuit position as shown in Fig. 4. That is to say, when the bridge blade d , extends transversely between the terminals C , C' , to close the circuit, as in Figs. 1, 2 and 3, the 100 spring pawl E , is free to retract beyond said bridge blade d , under the pressure of the helical spring h , but when the bridge blade makes the next quarter turn by the next depression of the spring pawl E through the 105 medium of the push button P , bringing the bridge plate d , into the position shown in Fig. 4, at right angles to the last preceding position and essentially in longitudinal alinement instead of transverse alinement 110 as in said Figs. 1, 2 and 3, then the retractile movement of the spring pawl E , will bring its hook shoulder e' , into contact with the concentric shoulder d^4 , on the end of the bridge plate d , adjacent to the push 115 button, causing contactual engagement between the said two shoulders d^4 , and e' , as indicated in Fig. 4, and shown in sectional detail in Fig. 10. As a result the push button P , will be locked against further retractile movement, the shoulder d^4 , on the bridge blade d , holding it against the resistance of the helical spring h , as shown in Fig. 4, and thereby exposing only the outer zone p^2 , of the stem p' , beyond the escutcheon S' , as shown in Fig. 4, and as this outer zone p^2 , is different in color or appearance 125 as compared with the inner zone p^3 , of said stem the observer will know that the push button is in depressed position and that the 130

electric circuit is open. On the contrary if both zones p^2 , p^3 , are visible it is an equally sure indication that the bridge plate is in contact with the terminal C, and that the electric circuit is closed.

I thus with a single push button attain all the advantages of a two button switch in so far as "reading" of set or circuit is concerned, with the added advantages of 10 simplicity and compactness of structure. Furthermore the helical spring h, substituted in lieu of the flat spring pawl shown in my concurrent application hereinbefore referred to is simpler and better adapted to 15 the requirements of my self-locking means for holding the push button depressed as above described to indicate the "open" of the circuit.

In this connection it is obvious that instead of providing zones on the stem of the push button like p^2 , and p^3 , of contrasting color, a like result may be attained by the use of other distinctive and contrasting means on different portions of the stem p' , 20 of the push button P, and hence by the term "contrasted zones" as used herein I mean to designate and include any difference in color, configuration or marking on the stem of the push button that will afford an equivalent result in indicating the set or position of the bridge blade d, and thereby affording visual information as to whether the electric circuit is open or closed.

What I claim as my invention and desire 25 to secure by Letters Patent is,

1. In an electric switch of the character designated, the combination of a rotatable circuit closer formed with diametrically opposed lateral shoulders and a ratchet hub, 30 and a spring pawl arranged to engage said ratchet hub to actuate the circuit closer and formed with a hook shoulder for contactual engagement with said lateral shoulders on the circuit closer, for the purpose set forth.

2. In an electric switch of the character designated, the combination of a base core of non-conducting material formed with a transverse central compartment, circuit terminals positioned therein, a rotatable circuit closer pivotally supported between the side walls of said compartment and between the terminals and formed with a ratchet hub and lateral shoulders beyond and on each side of said ratchet hub, a spring pawl arranged to engage with said ratchet hub to 45 actuate said circuit closer, said spring pawl being formed with a hook shoulder for contactual engagement with said lateral shoulders on the circuit closer when the latter is in open position, and a push button for actuating said spring pawl formed with a stem having contrasted zones, for the purpose described.

3. In an electric switch of the character designated, the combination of a base-core of 50 non-conducting material formed with diametrically opposed longitudinal side grooves, and with a transverse central compartment, circuit terminals positioned in the latter, a rotatable circuit closer pivotally supported 55 between the walls of said compartment and between said terminals and formed with a ratchet hub and lateral shoulders beyond and on each side of said ratchet hub, a push button provided with a stem having contrasted zones and with guide arms which extend into said longitudinal side grooves of the base-core and with a spring pawl for engaging with the ratchet hub on the circuit closer to actuate the latter, said pawl 60 being formed with a hook shoulder for contactual engagement with the said lateral shoulders on the circuit closer when the latter is in open position, and a helical spring interposed between said push button 65 and the inner end of the base-core, for the purpose described.

4. In an electric switch of the character designated, in combination, a base-core of 70 non-conducting material formed with diametrically opposed longitudinal side grooves and with a transverse central compartment, circuit terminals positioned in the latter, a rotatable circuit closer pivotally supported between the walls of said compartment and 75 between said terminals and formed with a ratchet hub, a push button provided with guide arms extending into said longitudinal side grooves on the base-core and with a spring pawl for engagement with the ratchet hub on the circuit closer to actuate the latter, and a helical spring interposed between said push button 80 and the inner end of the base-core, for the purpose described.

5. In an electric switch of the character 85 designated, the combination of a base-core of non-conducting material formed with a transverse central compartment, circuit terminals positioned therein, a rotatable circuit closer pivotally supported between the side 90 walls of said compartment and between the terminals and formed with a ratchet hub and lateral shoulders beyond and on each side of said ratchet hub, a spring pawl arranged to engage with said ratchet hub to 95 actuate said circuit closer, said spring pawl being formed with a hook shoulder for contactual engagement with said lateral shoulders on the circuit closer when the latter is in open position, and a push button for actuating said spring pawl, for the purpose 100 described.
